The ornamental design for the shroud for LED (light emitting diode) projection fixture, as shown and described.

DESCRIPTION

FIG. 1 is a front perspective view of the first embodiment of the shroud for LED (light emitting diode) projection fixture; FIG. 2 is a front perspective view of the second embodiment of the shroud for LED (light emitting diode) projection fixture; and,

FIG. 3 is a front perspective view of the third embodiment of the shroud for LED (light emitting diode) projection fixture.
